UNITED STATES PATENT OFFICE.

ANTONIO ALITTO, OF CHICAGO, ILLINOIS.

DESIGN FOR A COOKING-RANGE.

SPECIFICATION forming part of Design No. 29,145, dated August 2, 1898.

Application filed June 23, 1898. Serial No. 684,306. Term of patent 7 years.

To all whom it may concern:

Be it known that I, ANTONIO ALITTO, a citizen of the United States, and a resident of the city of Chicago, county of Cook, and State of

Illinois, have invented and produced a new and original Design for Cooking-Ranges, of which the following is a specification, reference being had to the accompanying drawing, forming part thereof.

10 The drawing is a perspective view of a cooking-range complete made in accordance with my design.

The material feature of my design is a rectangular frame having at the corners square posts *a* and between the corners, on the front side, vertical pieces *b b*, having parallel sides and extending from the floor. Between the pieces *b b* are panels *c*, *d*, and *e*, on which are ribs arranged in diamond-shaped forms. Double doors *f* and *g*, an oven-door *h*, a cinder-door *i*, and rails *k l* complete the

design of the body of the stove. The ends are represented by panels *m*, in the center of which is a handle *n*, only one end being shown, as the other end is an exact duplicate thereof.

Above the body of the range and at the back is a frame *o*, which supports a bracket *p*, to which is secured a cylindrical-shaped dish-warmer.

Having described my invention, what I claim as new, and desire to secure by Letters Patent, is—

The design for a cooking-range as herein shown and described.

In testimony whereof I affix my signature in presence of two witnesses.

ANTONIO ALITTO.
